Patented Dec. 17, 1918.

FIG. 1.

FIG. 3.

FIG. 2.

INVENTOR:

Manuel Egidio Baptista
by Chas. H. Luther

ATTORNEY

UNITED STATES PATENT OFFICE.

MANUEL EGIDIO BAPTISTA, OF NEW BEDFORD, MASSACHUSETTS.

ADJUSTABLE STAGING.

1,287,609.

Specification of Letters Patent.

Patented Dec. 17, 1918.

Application filed February 23, 1918. Serial No. 218,840.

To all whom it may concern:

Be it known that I, MANUEL EGIDIO BAPTISTA, a subject of Portugal, residing at New Bedford, in the county of Bristol and State 5 of Massachusetts, have invented a new and useful Improvement in Adjustable Stagings, of which the following is a specification.

My invention has reference to an improvement in building appliances and more particularly to an improvement in individual adjustable stagings or scaffoldings, for use in constructing, repairing, painting and washing the windows of buildings.

The object of my invention is to provide 15 an adjustable staging that can easily be handled by one man, that can easily and quickly be adjusted and attached to or detached from the window of a building and that can be separated and formed into a 20 comparatively light and compact bundle for carrying, packing or for storage purposes.

My invention consists in the peculiar and novel construction of an adjustable staging for individual use, said adjustable staging 25 having details of construction, as will be more fully set forth hereinafter and claimed.

Figure 1 is a vertical view of the wall of a building, in section and showing my 30 proved staging secured to a window-frame in a raised position, in full lines and in a lower position in broken lines.

Fig. 2 is a horizontal sectional view through the window-frame looking down 35 on the staging, and

Fig. 3 is an enlarged detail sectional view of one of the inner clamping ends of the staging.

In the drawings 4 indicates a portion of 40 the wall of a building in section, 5 a window-frame having the sides 6, 6, 7 the window-sill, 8 the outer window-cap and 9 my improved adjustable staging, as shown in Figs. 1 and 2.

The staging 9 consists principally when 45 set up, of two parallel horizontal platform bars 10, 10 adjustably connected at their outer ends by a transverse rod 11 and two angular parallel brace bars 12, 12 adjustably connected at their lower ends by a transverse rod 13. The horizontal platform bars 10, 10 each have a series of bolt holes 14, 14 adjacent their outer ends and the brace bars 12, 12 each have a corresponding series 50 of bolt holes 14, 14 adjacent their outer ends. The horizontal platform and truss

bars are pivotally and adjustably secured together adjacent their outer ends by bolts 15 passed through any desired pairs of holes 14 in the bars 10, the bolts being retained by 60 thumb-nuts 15', as shown in Figs. 1 and 2. The transverse rods 11 and 13 are each screw-threaded at their ends the required length for adjustment and are adjustably secured to the bars, through holes in the 65 bars, by thumb-nuts 16, 16 on the rods, one thumb-nut at each side of a bar, as shown in Fig. 2.

A clamping member 17 is formed on the inner end of each of the horizontal platform bars 10, 10. Each clamping member 17 is constructed to have a part 18 which bears against the outer face of the window-frame 5, a part 19 which lays against the runway of the window-frame and a part 20 parallel with the inner face of the window-frame and offset from the window-frame. A bolt slot 21 is formed in the part 19 and a clamping plate 22 bears against the inner face of the window-frame. The 75 clamping plate 22 has an L shaped end 23 which grips the inner edge of the window-frame and a screw-threaded stem 24 which extends through the slot 21 in the part 19 and is adjustably secured in place by a 80 thumb-nut 25 which bears against the outer face of the part 19. Two thumb-bolts 26, 26 are screw-threaded through the part 20 and bear at their inner ends against the clamping plate 22 and an intermediate coiled 85 spring 27 bears at one end on the part 20 and at its other end on the clamping plate 22, the spring pressure of the coiled spring 27 holding the clamping plate 22 in frictional contact with the window-frame, under 90 spring pressure.

In setting up the staging, the staging is adjusted for width, by adjusting the bars on the rods and the lower ends of the brace bars 12, 12 are placed on the window-sill 100 and the clamping members 17, 17 placed around the window-frame, the friction of the spring actuated clamping plates 22, 22 on the window-frame being sufficient to hold the staging in place while adjusting the staging for height. When the required height is obtained, by raising or lowering the clamping members 17, 17 on the window-frame, the thumb-nuts 25, 25 and the thumb-bolts 26, 26 are tightened, thereby rigidly 105 securing the staging to the window-frame. Boards are now laid across the horizontal 110

platform bars 10, 10 to form a platform on means for operating the clamping plate to 35 grip the edge of the window-frame. the staging, as shown in broken lines in Figs. 1 and 2.

The staging is adjustable for height and 5 width, it may be detachably secured to a window-frame and sill, as shown in full lines in Fig. 1 or it may be secured to the window-frame and the window-cap of a lower window, as shown in broken lines in 10 Fig. 1 and when taken apart it can be formed into a comparatively small and light bundle, for carrying or for storage purposes.

Having thus described my invention I claim as new:

15 1. In an adjustable staging having two parallel platform bars and two parallel brace bars pivotally secured to the platform bars, means for frictionally attaching and means for adjustably clamping the inner 20 ends of the platform bars to a window-frame consisting of a clamping member on the inner end of each platform bar, each clamping member having a part which bears against the outer face of the window-frame, 25 a part which bears against the runway of the window-frame, an offset part parallel with the window-frame, a clamping plate which bears against the inner face of the window-frame and is shaped to grip the 30 edge of the window-frame, thumb-bolts screw-threaded through the offset part and bearing against the clamping plate, an intermediate coiled spring engaging with the offset part and with the clamping plate and

2. An adjustable staging having the following instrumentalities, two parallel horizontal platform bars 10, 10, a transverse rod 11 adjustably connected at each end to a 40 platform bar, two parallel brace bars 12, 12, each pivotally and adjustably secured at its outer end to a platform bar, a transverse rod 13 adjustably connected at each end to a brace bar, a clamping member 17 formed on 45 the end of each platform bar, each clamping member 17 having a part 18 which bears against the outer face of a window-frame, a part 19 which bears against the runway of the window-frame, an offset part 20 parallel 50 with the inner face of the window-frame, a bolt slot 21 in the part 19, a clamping plate 22 which bears against the inner face of the window-frame and has an L shaped end 23 which grips the edge of the window-frame 55 and a screw-threaded stem 24 which extends through the slot 21, a thumb-nut 25 on the screw-threaded stem 24, thumb-bolts 26, 26 screw-threaded through the part 20 and bearing on the clamping plate 22 and an intermediate coiled spring 27 engaging at one 60 end with the part 20 and at its other end with the clamping plate 22, as shown and described.

In testimony whereof, I have signed my 65 name to this specification.

MANUEL EGIDIO BAPTISTA.
